Primary Examiner — Lauren D McVey

Assistant Examiner — Elisa Maria Pujals

(57) **CLAIM**

The ornamental design for a stuffed toy, as shown and described.

DESCRIPTION

FIG. 1 is a front and bottom perspective view of a stuffed toy, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines immediately adjacent to the shaded areas depict the bounds of the claimed design, while all other broken lines are directed to environment. The broken lines form no part of the claimed design.

1 Claim, 8 Drawing Sheets
